UNITED STATES PATENT OFFICE.

LOUIS GUTHRIE AND WILLIAM GRAY BAUMGARDNER, OF FILER CITY,
MICHIGAN.

COMBINED SCREEN AND STORM DOOR.

SPECIFICATION forming part of Letters Patent No. 363,740, dated May 24, 1887.

Application filed May 6, 1886. Serial No. 201,279. (No model.)

To all whom it may concern:

Be it known that we, LOUIS GUTHRIE and WILLIAM GRAY BAUMGARDNER, of Filer City, in the county of Manistee and State of Michigan, have invented a new and Improved Combined Screen and Storm Door, of which the following is a full, clear, and exact description.

The object of our invention is to provide a combined door which may be used either as a screen-door or as a storm door, this object being accomplished by means of panels which may be secured to or removed from the door.

Our invention consists in the construction and arrangement of parts, as will be herein-after fully described and claimed.

Reference is to be had to the accompanying drawings, forming a part of this specification, in which similar figures of reference indicate corresponding parts in all the figures.

Figure 1 is a view of the outer face of a two-panel door, the panels being shown as partially removed. Fig. 2 is a similar view of a four-panel door. Fig. 3 is a sectional plan view taken on line $x-x$ of Fig. 1, the removable panel being, however, shown in the closed position; and Fig. 4 is a sectional plan view taken on line $y-y$ of Fig. 2, the panels also being shown as closed.

In the drawings above referred to, 10 represents the stiles, and 11 the rails, that are arranged and fitted together in the ordinary manner. The stiles and rails are rabbeted in order to form a seat for the wire net or screen 12, strips 13 being fitted in the rabbets and 35 against the face of the net or screen. Upon the outer face of the door we secure moldings 15, that are formed with rabbets 16 and fitted together with miter-joints, as shown at 17, in order that there may be formed a way within 40 which to slide detachable panels 18, the molding 15 upon one side of the panel being secured thereto. These panels 18 may be made of any material desired, but for ordinary use we pre-

fer to make them of three-ply veneer; but in case it is desired to make the door burglar-proof the panels would preferably be made of sheet-iron.

In case of a four-panel door the molding is made double and secured to the central vertical bar of said door, as best shown in Fig. 4.

The door may be used as an ordinary screen-door by simply removing the panels and replacing the molding about the screen; but in case of stormy weather the panels would be inserted, and the door would answer the purpose of an ordinary storm door.

We are aware that a door has had a rabbeted opening in which a wire screen was secured, strips being secured around the edges of the screen on the rabbet, and a panel fitting removably in the rabbeted opening over the strips to cover the screen, and we do not claim the same as of our invention; but we are not aware that a door has had a screen over an opening therein, three edges of the opening 63 having rabbeted strips of molding, a panel sliding in the rabbets of the said strips and carrying a fourth strip of molding to complete border formed by the series of strips.

Having thus fully described our invention, what we claim as new, and desire to secure by Letters Patent, is—

A door having an opening therein, a screen covering said opening, rabbeted molding around three edges of said opening, a panel sliding in the ways formed by the rabbets of the molding, and a fourth piece of molding secured to the outer edge of the panel and completing the border formed by the said molding, substantially as set forth.

LOUIS GUTHRIE.
WILLIAM GRAY BAUMGARDNER.
